AQUARIUM AERATOR

Allan H. Willinger, New Rochelle, N.Y., assignor to
Metaframe Corporation, Maywood, N.J.

Filed Dec. 11, 1970, Ser. No. 26,415

Term of patent 14 years

Int. Cl. D30—99

U.S. Cl. D30—12

FIG. 1 is a front elevational view of an aquarium aerator showing my new design;
FIG. 2 is an elevational view of one side thereof;
FIG. 3 is an elevational view of the other side thereof;
FIG. 4 is a rear elevational view thereof;
FIG. 5 is a top plan view thereof; and
FIG. 6 is a bottom plan view thereof.

I claim:

The ornamental design for an aquarium aerator, substantially as shown.
